United States Patent Office

Des. 185,137
Patented May 12, 1959

185,137

STAND FOR POTTED PLANTS

Clarence E. De Melle, West Allis, Wis.

Application November 21, 1958, Serial No. 53,474

Term of patent 7 years

(Cl. D35—3)

Fig. 1 is a front elevational view of a stand for potted plants showing my new design;

Fig. 2 is a top plan view thereof; and

Fig. 3 is a right side elevational view thereof.

I claim:

The ornamental design for a stand for potted plants, as shown.
